EARL W. DENMAN, OF SWISSVALE, PENNSYLVANIA, ASSIGNOR TO WESTINGHOUSE ELECTRIC & MANUFACTURING COMPANY, A CORPORATION OF PENNSYLVANIA

MOTOR OPERATED TIME SWITCH

Application filed February 20, 1924. Serial No. 694,021.

My invention relates to electrical protective devices and particularly to motor-operated time switches.

One object of my invention is to provide a motor-operated time switch in which the clock is wound to a predetermined limit upon every operation of the motor before the switch is actuated by the motor.

Another object of my invention is to provide a time switch having a single motor for winding the clock and operating the switch.

Still another object of my invention is to provide a motor-operated time switch having a motor-wound clock and a locking means associated therewith for preventing the winding of the clock beyond a predetermined limit when the switch is actuated by the motor.

A further object of my invention is to provide a motor-operated time switch in which the motor imparts a predetermined torque to the time element, after which the motor actuates the switch.

In practicing my invention, I provide a motor for actuating a clock mechanism, and a snap switch. The motor is controlled by the clock mechanism for actuating the switch, and upon each operation of the motor, the clock mechanism is wound to a predetermined limit before the switch is actuated. With this disposition of parts, accurate operation of the clock may be insured because it is not required to perform any undue amount of work, as it merely controls a plurality of auxiliary switches in the motor circuit, thereby causing the motor to operate at predetermined intervals of time.

In the accompanying drawings,

Fig. 1 is a view, partially in elevation and partially in section, of a time switch embodying my invention;

Fig. 2 is a front view in elevation, of the device shown in Fig. 1;

Fig. 3 is a view, partially in plan and partially in section, along the line III-III of Fig. 2 of the auxiliary switch tripping mechanism;

Fig. 4 is a view, partially in elevation and partially in section, of an oil-immersed switch embodying my invention;

Fig. 5 is a side view in elevation of the device shown in Fig. 4, portions of the casing being broken for clearness;

Fig. 6 is a side view in elevation of the time element embodied in my invention, a locking device cooperating with the winding spring thereof and a modified form of an auxiliary switch tripping mechanism;

Fig. 7 is a sectional view taken along the line VII-VII of Fig. 6, showing a spring ⁶⁰ locking device;

Fig. 8 is a front view in elevation of the mechanism shown in Fig. 6;

Fig. 9 is a diagrammatic view of apparatus and circuits embodying the form of my invention shown in Figs. 1 and 2, respectively; and

Fig. 10 is a diagrammatic view of apparatus and circuits embodying the form of my invention shown in Figs. 4 and 5, respectively.

Referring to Figs. 1 and 2 of the drawings, a time switch 1 comprises, in general, a casing 2 in which is mounted a motor 3, a clock mechanism 4, a snap switch 5, and a tripping switch 6. The casing 2 is provided with an opening 7 in the bottom thereof to permit electric conductors (not shown) to be inserted for connection to a plurality of terminals 8. The casing 2 is also provided with a cover member 9 for enclosing same.

The clock mechanism 4 comprises an escapement 11, a winding gear 12, and a main spring 13 that is disposed in a supporting member 14 and operatively connected thereto at its outer end. The inner end of the spring 13 is connected to a shaft 15 upon which is mounted a gear 16 cooperating with the escapement 11. The shaft 15 is also provided with a time dial 17 having a toothed periphery 18 adapted to be engaged by indented portions 19 of a plurality of independent arms 21. The arms 21 are also provided with projections 22 that are adapted to cooperate with a tripping arm 23 of the tripping switch 6 for a purpose hereinafter described.

The outer portion of the time dial 17 adjacent to the toothed periphery 18 is divided, preferably, into 48 equal divisions, represent-

ing the 24 hours of a day, divided into half hour periods. The arms 21 are so set that the portions 19 register with markings on the time dial, corresponding to the desired time when the switch 5 is to be actuated, one of the arms 21 indicating the time the switch will close and the other of the arms 21 indicating the time the switch will open. The time dial 17 is rotatably driven counter-clockwise by the clock mechanism 4 through frictional engagement with a hub member 15a that is keyed to the shaft 15.

The time dial 17 is loosely mounted on the shaft 15 and is held in frictional engagement with the hub member 15a by a spring washer 17a. The time dial 17 can be manually rotated on the shaft 15 in a clockwise or counter-clockwise direction for the purpose of setting the clock to the correct time of the day.

The winding gear 12 is driven counter-clockwise by the motor 3 and is prevented from turning clockwise by a ratchet wheel 24 cooperating with a pawl member 25, adjacent to the winding gear 12. The pawl member 25 is held in engagement with the ratchet wheel 24 by a spring member 26.

As the time dial 17 is rotated, the arms 21 pass beneath a stationary pointer 27 at predetermined intervals of time and the projections 22 of the arms 21 engage the tripping arm 23, thereby actuating the tripping switch 6.

The tripping switch 6 comprises a plurality of cam members 28 and 29, adapted to cooperate with a plurality of switches 31 and 32, respectively, in the motor circuit. The cam faces of cam members 28 and 29 are in staggered relation with one another providing an alternate operation of the switches 31 and 32, respectively. A ratchet wheel 33 adjacent to the cam members 28 and 29 is rotated by a pawl member 34 pivotally mounted on the tripping arm 23 and held in engagement with the ratchet-wheel 33 by a spring 35. When the tripping arm 23 is actuated, the ratchet-wheel 33 and the cam members 28 and 29 are rotated, simultaneously closing one of the switches 31 and 32 and permitting the other switch to open.

When the one or the other of the switches 31 and 32 is closed, the motor 3 will operate to wind the main spring 13 of the clock 4 through a differential gear 36 and a gear train 37, until the main spring 13 is wound to a predetermined limit. When the main spring 13 is wound to its maximum limit, the motor 3 will continue to function through the differential gear 36 and a gear train 38 to the snap switch 5, for the actuation thereof to its open or closed position.

The snap switch 5 comprises a spindle 39, upon which is mounted a gear 41 cooperating with the gear train 38, and a plurality of bridging contact members 42 and 43, insu-

lated therefrom. The members 42 and 43 cooperate with a plurality of stationary contact members 44, 45 and 46, 47, 48 and 49, respectively. A torsion spring 51 is disposed on the spindle 39 having one end connected to the spindle 39, and the other end connected to the bridging contact members 42 and 43 to actuate the latter.

A mechanism, of any type well-known in the art, for imparting a snap action to the switch 5 is disposed at the inner end of the spindle 39 of the switch 5. The motor 3 rotates the spindle 39, causing the spring 51 to be wound until the torsional forces therein overcome the frictional force of the switch 5, and at the same time actuating the snap-action mechanism, thereby permitting the switch 5 to snap into its open or its closed position, as the case may be.

A skip-day device 52 adapted to open the motor circuit, for preventing the switch 5 from operating during a 24-hour period, is actuated by the clock mechanism 4 through a gear train 53. The device 52 comprises a shaft 54 having a gear 55 disposed thereon and a dial 56 disposed at the outer end thereof. A cam member 57 having an integral arm 58 is rotatably disposed on the shaft 54 adjacent to the dial 56. The arm 58 extends beyond the edge of the dial 56, the outer end thereof having an indented portion 59 that is adapted to cooperate with any one of a plurality of depressions 61 equally spaced around the periphery of the dial 56.

The dial 56 is provided with markings, dividing the portion adjacent the periphery into 7 equal divisions, each having one of the depressions 61 therein. Each division represents one day of the week.

When it is desired to maintain the switch 5 inoperative for any one day, the arm 58 is set so that the portion 59 registers with the depression 61 corresponding to the desired day. The dial 56 is rotated by the clock mechanism 4, and the dial in turn rotates the cam member 57 therewith until the cam member 57 engages a cooperating cam member 62 of a skip-day switch 63, thereby actuating the switch and opening the motor circuit. The switch 63 is in series connection with the switches 31 and 32. The switch 63 is held open so long as the cam 57 is in engagement with the cam portion 62, thereby preventing actuation of switch 5 during the period of engagement of said cam members.

Referring to Figs. 6 and 7, a spring locking device 64 is disposed adjacent to the spring supporting member 14, for preventing the spring 13 from being wound beyond a predetermined limit. The spring locking device 64 is provided with a gear wheel 65, adapted to cooperate with a pinion 66 disposed on the shaft 15. The gear wheel 65 is rotatably mounted on a spindle 67 that is integral with the spring supporting member

14 and a latch member 68, also supported by the spindle 67 adjacent to the gear 65, is adapted to be turned into engagement with the teeth of the pinion 66, thereby preventing further rotation of the winding gear 12. A pin 69 integral with the gear 65 is adapted for engaging the latch member 68 and bringing it into engagement with the pinion 66, as shown in broken lines in Fig. 7.

10 The gear wheel 65 rotates about the pinion 66, the pin 69 carried thereby making one revolution before it engages the latch member 68. The clock spring 13 can be wound to run the clock mechanism 4 for several days 15 with one winding, the length of running time depending upon the gear-ratio of the gear wheel 65 and the pinion 66.

10 The spring locking device 64 also prevents the clock spring 13 from unwinding beyond 20 a predetermined limit, should the clock run for several days without having been wound. During the period that the clock spring 13 is unwinding, the gear wheel 65 is rotated in a clockwise direction and upon its second 25 revolution engages the latch member 68 and moves it into engagement with the teeth of the pinion 66, as shown in dot-and-dash lines in Fig. 7, thereby preventing further operation of the clock mechanism 4 until the clock 30 spring 13 is rewound.

25 A modified form of the auxiliary switch tripping mechanism from that shown in Figs. 1 and 2 is shown in Figs. 6 and 8, comprising a star-wheel 71 mounted on a shaft 72, and a plurality of cam members 73 and 74 also carried by the shaft 72 adjacent the star-wheel 71. The cam members 73 and 74 are provided with a plurality of cam-faces 75 and 76, respectively, that are in staggered 40 relation with one another. The cam members 73 and 74 are rotated simultaneously with the star-wheel 71 and their cam-faces 75 and 76 engage the horizontally mounted switches 31 and 32, respectively, for controlling the motor.

45 A clear understanding of the electrical connections used with the apparatus shown in Figs. 1 and 2 may be had by referring to Fig. 9 in which electric conductors 77 and 78 are connected to the stationary contact members 45 and 48, respectively, of the switch 5. A second pair of electric conductors 79 and 81 are connected from the stationary contact members 44 and 46, respectively, of the switch 5, to an electrical apparatus, (not shown), to be time controlled.

Upon closing switch 5, the movable bridging contact member 42 will bridge the stationary contact members 44 and 45, and the movable bridging contact member 43 will bridge the stationary contact members 46 and 48, thereby establishing a circuit through the switch 5.

50 When the switch 5 is closed, the current of the controlled circuit will traverse a circuit

from conductor 77 through stationary contact member 45, bridging member 42, stationary contact member 44, conductor 79, through an electrical apparatus (not shown), conductor 81, stationary contact member 46, 70 bridging member 43 and stationary contact member 48 to conductor 78.

55 A motor circuit comprises a plurality of conductors 82, 83 and 84 connected to the stationary contacts 47, 46 and 45, respectively, of switch 5. The switch 5 is shown in the open position with respect to the controlled circuit, but the motor circuit is closed and the motor 3 is in the operation of winding the clock mechanism. The motor circuit 60 then extends from the conductor 78, through the stationary contact member 49, bridging member 43, stationary contact member 47, conductor 82, switch 31, skip-day switch 63, 65 motor 3, conductor 84 and stationary contact member 45, to the conductor 77. This circuit is interrupted between the members 43 and 47 when the switch 5 is actuated to its closed position by the motor 3.

70 When the switch 5 is in its closed position, the bridging contact member 43 is placed in a second motor circuit that is not completely established until the switch 32 is closed by the auxiliary tripping switch 6. The motor circuit then extends from conductor 78, 75 through the stationary contact member 48, bridging contact member 43, stationary contact member 46, conductor 83, switch 32, skip-day switch 63, motor 3, conductor 84 and stationary contact member 45 to the conductor 77.

80 In Figs. 4 and 5 of the drawings, I have illustrated another form of the device, wherein in the mechanism, employed with the air-snap switch 5 in Figs. 1 and 2, is employed 85 with an oil switch 85. Certain reference numerals used in Figs. 1 and 2 are used to designate like elements in Figs. 4 and 5. The timing mechanism 4 is enclosed within a suitable casing 86 having a cover 87. The casing 90 90 is provided with a plurality of electrical terminals 88 for electrically connecting the motor 3 contained therein, with the oil switch 85.

95 The oil switch 85 is disposed within a suitable casing 89, and cover 91 whose inner side is provided with depending lugs 92, to which the switch panel 93 is secured by screws 94. The casing 89 includes a removable container 95, that is held in position by a plurality of latch members 96. The container 95 contains an insulating medium 97, such as oil, in which the oil switch 85 is immersed. A plurality of electric terminals 98, cooperating 100 with the switch 85, extend through the top portion 91 of the casing 89 and are insulated therefrom by a plurality of bushings or insulators 99.

105 The switch 85 is mounted upon the panel 93 that also supports two sets of stationary 110

switch-jaw members 101 and 102, between which a switch shaft 103 is mounted upon bearings 104 and 105. The shaft 103 carries a switch-blade member 106 for each pair 5 of switch-jaws 101 and 102 and is operated by means of a toothed arm or rack member 107 that cooperates with a gear sector 108 loosely supported on the shaft 103 and secured to the blade member or members 106. 10 A switch operating mechanism 109, that may be of any preferred type, so connects the gear sector 108 with the switch shaft 103 that a predetermined angular movement of the gear sector 108 causes the switch-blade members 106 to rotate into or out of engagement with the switch-jaw members 101 and 102 with a snap action.

As mechanisms for imparting a snap action to switch shafts are old and well-known 20 in the art, and as the mechanism herein illustrated forms no part of my invention, except insofar as it is necessary to complete the combination with the other elements of the invention, it is believed to be unnecessary to 25 here describe in detail the operation of this device. It will be understood, however, that the switch action is such that, when the gear sector 108 is turned substantially through 90° in either clockwise or counter-clockwise 30 direction, the switch-blade member or members 106 are actuated to either engage or disengage the switch-jaw members 101 and 102.

The rack member 107 is held substantially 35 in engagement with the gear sector 108 by a roller 111. The end of the rack member 107, opposite the toothed portion, is supported by a crank arm 112 that is fixedly mounted on one end of a rotatable shaft 113, the other 40 end of which supports a gear wheel 114 co-operating with the gear train 38.

A clear understanding of the electrical connections used in the device shown in Figs. 4 and 5 may be had by referring to Fig. 10, 45 in which electric conductors 115 and 116 are connected to one pair of the terminals 98 of the switch 85. A second pair of electric conductors 117 and 118 connect the other 50 pair of terminals 98 of the switch 85 to an electrical apparatus (not shown) to be time controlled.

Upon closing switch 85, the movable bridging contact members 106 will bridge the stationary contact members 101 and 102, thereby 55 establishing a circuit through the switch 85.

When the switch 85 is closed, the current of the controlled circuit will traverse a circuit from conductor 115 through terminal 98, stationary contact member 101, bridging contact member 106, stationary contact member 102, terminal 98, conductor 117, through an electrical apparatus (not shown) conductor 118, terminal 98, stationary contact member 102, bridging contact member 106, stationary con-

tact member 101 and terminal 98 to conductor 116.

A motor circuit comprising a plurality of conductors 119 and 121 is also connected through the switch 85 for operating the 70 motor. The conductor 119 is indirectly connected to one of the blade members 106. The switch 85 is shown in its closed position, and the motor 3 is in the operation of winding the clock mechanism 4, then the motor circuit extends from the conductor 119 through the switch-blade member 106, switch-jaw 102, conductor 122, terminal 88, conductor 123, contactor switch 31, skip-day switch 63 and the motor 3 to the conductor 121. This circuit is maintained until the switch 85 is actuated, at which time the motor circuit will be opened by the separation of the switch-blade 106 from the switch-jaws 102.

When the switch 85 is in its open position 85 with respect to the controlled circuit, the switch-blade 106 that is connected in the motor circuit will be in engagement with the switch-jaw 101, but the motor circuit will still be broken due to the fact that the switch 32 90 is being held open by the auxiliary tripping switch 6. When the tripping switch mechanism 6 is actuated to permit the closing of the switch 32, the motor circuit will be then closed and the circuit will extend from conductor 95 119, through the switch-blade member 106, switch-jaw 101, conductor 124, terminal 88, conductor 125, switch 32, skip-day switch 63 and motor 3 through conductor 121.

By my invention, I provide a dependable 100 motor-actuated time switch, the operation of which may be exceedingly accurate as the clock spring is not required to do any work except to control the motor, the switch being actuated by the direct motor drive.

Various modifications and changes may be 105 made in details and I desire, therefore, that only such limitations shall be imposed as are set forth in the appended claims.

I claim as my invention:

1. In a time switch, an electric motor, a clock, a switch actuated upon every operation of said motor and means whereby said clock is wound to a predetermined limit upon every 115 operation of said motor, before the operation of said switch.

2. In a time switch, a motor, a clock, a snap switch actuated by said motor, and a differential gear-train for transmitting energy from said motor through said differential gear for winding said clock to a predetermined limit and for actuating said switch upon every operation of said motor.

3. In a time switch, a motor, a clock, a snap switch actuated by said motor, a differential gear, a plurality of gear-trains cooperating with said differential gear for transmitting energy from said motor for winding said clock and for actuating said snap switch after 130

said clock has been wound to a predetermined limit upon every operation of said motor.

4. In a time switch, a motor, a clock mechanism, a rotatable switch actuated by said motor, and a gear-train comprising a differential gear and a plurality of gear wheels cooperating therewith, whereby mechanical energy is transmitted from said motor upon every operation thereof for winding the 10 spring of said clock mechanism to a predetermined limit just prior to each movement of said switch.

5. In a time switch, a motor, a clock, a switch, a connecting gear-train, and a contactor device comprising a plurality of spring contactors, a plurality of cam members cooperating therewith, and means for periodically turning said cam members and thereby causing one set of contactors to close when a 15 second set is opened, said contactors being connected to energize said motor for winding said clock and actuating said switch.

6. In an electrical system, a motor, a switch, a clock, means for connecting said 20 motor to the spring of the clock and to the switch, a plurality of switches for controlling the operation of said motor, and a plurality of cam members for actuating the last-named switches alternatively in accordance 25 with predetermined conditions of time, said motor also being controlled by the position of the first-named switch.

7. In an electrical system, a motor, a switch, a clock, means for mechanically connecting 30 said motor to the spring of the clock and to the switch, a plurality of switches for starting the operation of said motor upon the closing of one of the last-named switches, and means for stopping the motor upon the operation of the first-named switch.

8. In a time switch, the combination with a motor, a clock adapted to be wound by said motor and a switch actuated thereby, of a locking device for preventing overwinding 45 of said clock, said locking device comprising a gear, a pawl member adjacent said gear, means carried by said gear adapted to engage said pawl member, and a pinion mounted on the time-recording shaft of said clock 50 and cooperating with said gear of the locking device adapted to be engaged by said pawl member when said clock is wound to its predetermined maximum limit.

9. In an electric time switch, the combination with a motor wound clock and a motor 55 operated switch, said clock having a winding gear, a main spring, a spring supporting member adjacent to said winding gear, a driven time shaft adapted to extend through said spring supporting member and cooperating with said main spring, and a time driving gear disposed on said driven shaft, of a locking device disposed adjacent to said spring supporting member and said time 60 driving gear, comprising a shaft secured to

said spring supporting member, a gear disposed on said shaft, a pawl member loosely mounted on said shaft adjacent said gear, a pin integral with said gear and adapted to engage said pawl member, a pinion secured to said time shaft and cooperating with said gear supported by the spring enclosing member, said pinion being engaged by said pawl member when said clock has been wound to a predetermined limit, thereby preventing excessive winding of said clock.

10. A time-switch including a clock mechanism having a main spring and a time-controlled mechanism, in combination with a switch, an electric motor and means actuated by the time-controlled mechanism for operating the motor to wind the clock spring and to operate the switch at every actuation of said time controlled mechanism.

11. A time-switch including a clock mechanism having a main spring and a time-controlled mechanism, in combination with a switch, an electric motor, and means actuated by the time-controlled mechanism for starting the motor to wind the clock spring and to operate the switch, said motor being so connected that the operation of said switch stops the motor.

12. A time switch including a clock, a main switch, and time controlled means actuated by said clock at predetermined intervals, said main switch being operated by an electric motor, the circuit of said motor being closed by said time controlled means to operate said switch at said predetermined intervals.

13. A time switch including a clock, a main switch, and time controlled means actuated by said clock at predetermined intervals, said main switch being operated by an electric motor, the circuit of said motor being closed by said time controlled means to operate said switch at said predetermined intervals, and means for winding said clock by said motor at said predetermined intervals.

14. A time switch including a clock, a main switch, and time controlled means actuated by said clock at predetermined intervals, said main switch being operated by an electric motor, the circuit of said motor being closed by said time controlled means to operate said switch at said predetermined intervals and means for winding said clock by said motor at said predetermined intervals, the winding of said clock and the operation of said switch taking place successively.

15. A time switch including a clock, a main switch, and time controlled means actuated by said clock at predetermined intervals, said main switch being operated by an electric motor, the circuit of said motor being closed by said time controlled means to operate said switch at said predetermined intervals, and the circuit of said motor being opened by the operation of said switch.

16. A time switch including a clock, a main

switch, and time controlled means actuated by said clock at predetermined intervals, said main switch being operated by an electric motor, the circuit of said motor being closed by said time controlled means to operate said switch at said predetermined intervals and means for winding said clock by said motor at said predetermined intervals, the winding of said clock taking place prior to the operation of said switch.

17. A time switch including a clock, a main switch, and time controlled means actuated by said clock at predetermined intervals, said main switch being operated by an electric motor, the circuit of said motor being closed by said time controlled means to operate said switch at said predetermined intervals and means for winding said clock by said motor at said predetermined intervals, the winding of said clock taking place prior to the operation of said switch, and the circuit of said motor being opened by the operation of said switch.

In testimony whereof, I have hereunto subscribed my name this first day of February, 1924.

EARL W. DENMAN.
